Int. Cl. D21—02

U.S. Cl. D34—5

FIG. 1 is a front elevational view of combined blocks and three dimensional game board showing my new design.

FIG. 2 is a side elevational view thereof; and

FIG. 3 is a top plan view shown fragmentarily for convenience to illustration.

The back surfaces of the board are plain and unornamented, having turned-in guide strips receiving a plate-like member, the side edge of the latter being shown in FIG. 2 and a top edge thereof being shown in FIG. 3.

I claim:

The ornamental design for combined blocks and three dimensional game board, as shown and described.
